UNITED STATES PATENT OFFICE

160,190

PORTABLE TRAFFIC LIGHT

Le Roy May, Paris, Ill.

Application December 3, 1949, Serial No. 6,407

Term of patent 14 years

(Cl. D72—1)

To all whom it may concern:

Be it known that I, Le Roy May, residing at Paris, State of Illinois, have invented a new, original, and ornamental Design for a Portable Traffic Light, of which the following is a specification, reference being had to the accompanying drawings, forming a part hereof.

Fig. 1 is a side elevational view of a portable traffic light showing my new design.

Fig. 2 is a rear elevational view thereof, and,

Fig. 3 is a top plan view.

I claim:

The ornamental design for a portable traffic light, as shown.

LE ROY MAY.
